DESIGN FOR A STOVE.

Design No. 12,609, dated December 20, 1881.

Cut 266.

UNITED STATES PATENT OFFICE.

H. CLAY BASCOM, OF TROY, AND TOBIAS S. HEISTER, OF LANSINGBURG,
ASSIGNORS TO N. S. VEDDER PATTERN WORKS, BASCOM, GALBRAITH
& CO., OF TROY, NEW YORK.

DESIGN FOR A STOVE.

SPECIFICATION forming part of Design No. 12,609, dated December 20, 1881.

Application filed November 19, 1881. Term of patent 7 years.

To all whom it may concern:

Be it known that we, H. CLAY BASCOM, a citizen of the United States, residing in the city of Troy, in the county of Rensselaer and 5 State of New York, and TOBIAS S. HEISTER, a citizen of the United States, residing in the village of Lansingburg, in said county and State, have jointly invented and produced a new and original Design for a Franklin Stove, 10 of which the following is a specification, reference being had to the accompanying print, cut, or engraving of a stove having said new design.

The design for the top portion, A, consists 15 of the urn B, having the series of heart-shaped ornaments c, in combination with the quadrilateral dome-form plate D, having the outer series of arched-top apertures e and the partial rosettes f, all shaped and arranged so 20 as to present the appearance represented in the accompanying engraving.

The design for the corner pilasters, G, consists of the reversely-arranged top and bottom fan-form ornaments, h h', and the intervening 25 in-cut ornaments, i, and plant ornaments j, having linear and pinuate leaves k k' and terminal flowers l, all shaped and disposed substantially as shown in the aforesaid cut.

The design for the upper front portion, M, 30 consists of the lower swelled forwardly-projecting flat-arched part, having the middle upwardly-extending multi-radiate ornament n, downwardly-extending semicircular ornament o, and parti-rosette p, with lateral leaf ornaments q and top serrate arch, r, in combina-

tion with the star-filled upper ornamental panels, s, and corner ornaments, t, all shaped and arranged together substantially as shown in the aforesaid print.

The design for the lower section, U, consists 40 of the projecting base-plate v, overhanging top plate, w, upright end plate having the series of ellipsoidal ornamented panels x, and the upright front door having the series of star ornamentations y and intermediate round-top apertures, z, all shaped and arranged together as represented in the aforesaid cut.

What we claim as our joint invention is—

1. The design for the top portion, A, consisting of the parts B c and D e f, all shaped 50 and arranged substantially as shown and described.

2. The design for the corner pilasters, G, consisting of the ornamental parts h h' i j k k' l, all shaped and arranged as set forth. 55

3. The design for the upper front portion, M, composed of the ornamental parts n o p q r s t, all shaped and arranged as set forth.

4. The design for the lower section, U, composed of the parts v w x y z, all shaped and arranged together as shown and described. 60

In testimony whereof we hereunto set our hands, in the presence of two subscribing witnesses, this 17th day of November, 1881.

H. CLAY BASCOM.
TOBIAS S. HEISTER.

Witnesses:

AUSTIN F. PARK,
JAMES T. GOODFELLOW.
